UNITED STATES PATENT OFFICE

154,789

DESIGN FOR AN AUTOMOBILE VISOR

William A. Maher, Detroit, Mich.

Application August 9, 1947, Serial No. 140,804

Term of patent 3½ years

(Cl. D14—6)

To all whom it may concern:

Be it known that I, William A. Maher, a citizen of the United States, residing in Detroit, in the county of Wayne, State of Michigan, have invented a new, original, and ornamental Design for Automobile Visor, of which the following is a specification, reference being had to the accompanying drawing, forming a part thereof, wherein:

Fig. 1 is a plan view of an automobile visor, showing my new design;

Fig. 2 is a front edge view of the visor shown in Fig. 1;

Fig. 3 is a bottom plan view of the visor shown in the preceding views;

Fig. 4 is a perspective view of the visor shown in the foregoing views, showing its relation to an automobile body when mounted thereon, the automobile body being shown fragmentarily by dot and dash lines and for illustrative purposes only.

The dominant features of my design reside in the portions shown by means of full line in the drawing and particularly the contrasting appearance of the end portions.

I claim:

The ornamental design for an automobile visor, as shown and described.

WILLIAM A. MAHER.
